EXHAUST DEFLECTOR

John De Mooy, Shaker Heights, Ohio, assignor
to The Cleveland Pneumatic Tool Company,
Cleveland, Ohio, a corporation of Ohio

Application March 14, 1934, Serial No. 715,460

5 Claims. (Cl. 121—35)

This invention relates broadly to fluid actuated tools, but more particularly to the construction of exhaust deflector therefor.

One object of this invention is to produce a novel, simple, and effective device for deflecting the fluid exhausting from a fluid actuated machine away from the operator. Another object of this invention is to provide a fluid actuated machine with a combined exhaust deflecting and 10 exhaust controlling device susceptible of ready manipulation.

These objects are accomplished by a construction free of complication, and by arrangement of parts resulting in a compact unit which is strong, durable, and efficient.

In the drawing which illustrates a preferred embodiment of the invention:

Fig. 1 is a longitudinal view partly in section of a fluid actuated tool embodying the invention. 20 Fig. 2 is an enlarged longitudinal cross sectional view illustrating the exhaust deflector in one position.

Fig. 3 is a view similar to Fig. 2, illustrating the exhaust deflector in another position.

Referring to the drawing in which like symbols designate corresponding parts throughout the several views, 10 represents the casing or cylinder of a fluid actuated percussive tool having secured thereto a handle 11. Within the handle 11, there is incorporated a throttle valve operable by a throttle handle or lever 12. Reciprocably mounted within the cylinder 10, there is the usual piston 13 which is responsive to the action of the pressure fluid admitted into the cylinder 30 through passages 14. The admission of the pressure fluid into these passages may be either piston or valve controlled, but since this portion of the mechanism does not constitute a part of the present invention, no further description 35 through 40 of the same is thought necessary. Slidably mounted within the front end of the cylinder 10, there is a tool implement 15 adapted to receive the blows of the piston 13.

Referring now more particularly to the present 45 invention, 16 represents an exhaust port leading from the interior of the cylinder 10 to the atmosphere, through which pressure fluid admitted into the former is normally free to exhaust therefrom when the piston reaches the ends of 50 its strokes. Adjacent the exhaust port 16, the external wall of the cylinder is formed with an annular groove 17 adapted to receive the constricted end coil 18 of a compression spring 19, the latter being of a normal inner diameter 55 somewhat greater than the external diameter

of the cylinder 10. The spring 19 is completely surrounded or circumscribed by an exhaust deflecting hood or sleeve 20. The ends of the latter are machined to provide internal flanges 21 and 22 forming abutments engaging the end coils of the spring 19 for securing the sleeve 20 to the cylinder in slidable and rotatable relation therewith. Radially disposed through the sleeve 20, there is an orifice 23, of a diameter substantially equal to that of the exhaust port 16.

In assembling the device, the spring 19 is first introduced into the sleeve 20 by screwing the former over one of the turned flanges 21 or 22. To cause the opening of the constricted coil 18 when the spring and sleeve are introduced over the cylinder, the front end of the latter is beveled as at 24. Subsequently, the sleeve and spring are simply pushed upwardly on the cylinder until the coil spring 18 drops into the groove 17. When it is desired to remove the deflector 20 from the cylinder, sufficient downward pressure must be applied on the sleeve 20 to cause the constricted coil spring 18 to open and slip out of the groove 17.

The constricted coil end spring 18 being of a normal diameter somewhat smaller than that of the groove 17, will exert enough clamping action on the cylinder to permit the full compression of the spring in a solid member when sufficient upward pressure is applied to the sleeve 20. In this instance, the spring fully covers the exhaust port 16, thus preventing the exhaust of the pressure fluid from the cylinder 10. The amount of pressure fluid exhausting from the cylinder may also be varied by somewhat releasing the upward pressure applied on the sleeve 20, thus permitting a more or less complete separation of the coils of the spring 19.

The radial angle at which the pressure fluid is exhausting from the cylinder 10 may be varied 40 by simply rotating the sleeve 20, since the fluid escaping through the exhaust port 16 is admitted into the sleeve and escapes through the port 23 irrespective of the position of the latter with port 16.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

I claim:

1. In a fluid actuated tool, the combination with a cylinder having an exhaust port, an exhaust controlling device comprising a member secured to said cylinder and movable in exhaust port open or closed position, and an exhaust deflector normally rotatably supported by said member.
2. In a fluid actuated tool, the combination of 10 a casing having an exhaust port, an exhaust controlling member mounted on said casing and movable for opening and closing said exhaust port, and an exhaust deflector mounted on said casing and supported by said controlling member, said deflector movable on said casing for actuating said member for closing the exhaust port.
3. In a fluid actuated tool, the combination of 20 a casing having an exhaust port, a coil spring secured at its upper end to said casing, and an exhaust deflecting member completely circumscribing said spring and supported thereby in a

manner whereby said member is capable of relative rotation with respect to said spring and exhaust port of the casing.

4. In a fluid actuated tool, the combination of 5 a casing having an exhaust port, an exhaust hood formed with an aperture rotatable in variable angular relation with respect to said port, and a coil spring carried by said cylinder circumscribed within said hood for supporting the latter, said spring upon longitudinal movement 10 of said hood being capable of compression to close said exhaust port.

5. In a fluid actuated tool, the combination with a cylinder having an exhaust port, a coil spring circumscribing said cylinder and formed 15 with a coil smaller than the other coils thereof, an external annular groove on said cylinder adapted to receive said smaller coil in spring supporting relation, and an exhaust deflecting member rotatably supported by said spring. 20

JOHN DE MOY.
